UNITED STATES PATENT OFFICE.

ROBERT L. CHOPE, OF DETROIT, MICHIGAN.

COIN-WRAPPER.

SPECIFICATION forming part of Letters Patent No. 595,763, dated December 21, 1897.

Application filed July 16, 1896. Serial No. 599,374. (No model.)

To all whom it may concern:

Be it known that I, ROBERT L. CHOPE, a citizen of the United States, residing at Detroit, in the county of Wayne and State of Michigan, have invented certain new and useful Improvements in Coin-Wrappers, of which the following is a specification, reference being had therein to the accompanying drawings.

10 The invention consists in the construction of a coin-wrapper made of light flexible material—such, for instance, as paper—comprising a wrapping-strip formed with a series of articulations or sections hinged together, having means for preventing the coin from being displaced longitudinally and means for securing the ends of the wrapping-strip together, and, further, in the construction, arrangement, and combination of the various 20 parts, all as more fully hereinafter described.

In the drawings, Figure 1 is a perspective view of my improved coin-wrapper, showing it in position ready to receive the coin. Fig. 2 is a similar view showing it in position for 25 packing, for shipment, or storage. Fig. 3 is a vertical central section through the package complete, showing the coin therein. Fig. 4 is an end elevation, partly in section. Figs. 5 and 6 are cross-sections, centrally through 30 Fig. 1, showing slightly different constructions of wrapping-strip.

In making the wrapping-strip proper I may take a single piece of paper and fold it upon itself, as shown in Fig. 5, cementing 35 the overlapping portions together, or I may take two strips of paper, as shown in Fig. 6, and cement these together to form the body of the wrapping-strip A. This wrapping-strip at the margin or at the sides is provided with 40 an inwardly-extending flange or teeth B, preferably separated tapering teeth, as shown in the drawings. The strip is provided with transverse grooves or creases C, which divide the strip into a series of sections D, hinged 45 together at the creases so as to form an articulated wrapping-strip. The teeth B are preferably formed at the ends of the sections D, and each tooth is preferably formed with a bead or a rib E around the corner, as plainly 50 shown in Figs. 3 and 3, thus acting as a stiffener or truss for this tooth to resist the movement of the coin in the wrapper from

endwise displacement. The wrapper thus formed and the crease being formed on the inner side will naturally assume a curved 55 shape, as shown in Fig. 1, and this curved shape is not satisfactory for packing purposes. To pack the wrappers in packages for shipment, I straighten them out, and to keep them in this straight position I form a 60 longitudinal groove F in the body of the wrapper, on which it may be bent into a trough shape, as shown in Fig. 2, and when in this position the wrappers may be stacked up one upon the other to take up the least 65 possible room and bunched tightly together, so as to prevent any possible damage in shipment. When it is desired to use one of these wrappers, it may be taken from the package and then by a pressure of the finger centrally 70 upon the raised portion of the wrapper-strip it will spring into the shape shown in Fig. 1, in which position it may be readily filled while being held in the hand.

I provide suitable means for holding the 75 ends of the wrapper-strip together, but prefer to use a thin flap G, gummed on its inner face, secured to one end of the wrapper-strip. It has been found in practice that if this strip is simply a flat piece of paper it often will 80 stick so insecurely in hurried use as to cause the wrapper to open in being handled. I find this can largely be obviated by forming on the gummed side of the paper a series of 85 creases or longitudinal indentations H, so arranged as to leave portions I unbroken or creased to give the proper strength to the flap, for this creasing affects more or less the strength of the paper. I find that with the gummed strip so creased it assumes so much 90 more readily the circular shape of the coin that even if but slightly moistened and quickly pressed, as is done in hurried use, it will stick much tighter than a plain strip. It will be observed that the indentations or 95 creases do not extend through the pasting-strip, but are rather in the form of grooves in the surface of the strip and do not weaken the strip, as would cuts or slits.

The terms "indentations" and "creases" 100 in this specification are used in contradistinction to "cuts" and "slits."

A coin-wrapper thus constructed has the following advantages arising from the con-

struction described: The first cost is reduced, the strength is increased, it can be packed and shipped in the smallest possible space, and it can be more quickly and securely sealed than with the old structures.

5 What I claim as my invention is—

1. A coin-wrapper, comprising a single strip of flexible material, provided with transverse creases or scores, and upturned marginal teeth or flanges each provided with a stiffening-rib, and means for securing the strip about the coin, substantially as described.
- 10 2. A coin-wrapper comprising a strip of articulated sections, upturned marginal flanges on said sections, each provided with a stiffening rib or bead, and means for securing the strip about the coin, substantially as described.
- 15 3. A coin-wrapper comprising a strip formed with upturned marginal teeth or flanges each formed with a stiffening bead or rib, substantially as described.
- 20 4. A coin-wrapper comprising a strip provided along its opposite edges with teeth or flanges having provision for maintaining the same at substantially right angles to the strip,
- 25

and also provided with a crease or score extending in a direction parallel with said teeth or flanges, whereby the strip can be bent for nesting purposes.

5. In a coin-wrapper, a strip bent or folded upon itself and cemented, and provided with transverse scores or creases, and a longitudinal crease, and upturned marginal teeth or flanges, between the transverse scores or creases and extending at right angles to the strip, substantially as and for the purposes set forth.

10 6. A coin-wrapper comprising a single strip, of parts folded upon itself and cemented, and provided with transverse creases or scores and upturned marginal teeth or flanges each of which is formed with a bead or rib, and means for securing the strip about the coin, substantially as described.

15 In testimony whereof I affix my signature in presence of two witnesses.
